ELECTRICAL TERMINAL CLASP CONNECTOR

Maxwell A. Graham, Elizabeth, N. J., assignor to
The Thomas & Betts Co., Elizabeth, N. J., a corporation of New Jersey

Application June 4, 1947, Serial No. 752,444

15 Claims. (Cl. 287—76)

1

This invention relates to electrical connectors and more particularly to improvements in respect to the duplicate-form type or class thereof known in the art to comprise a pair of identical-form terminals disengageably connected to produce a complete fitting. For convenience, the new electrical quick-disconnect fitting herein may be referred to as an electrical terminal clasp connector.

Known connectors of this general class sometimes are referred to as twin connectors since two identical-half parts (or the engaging portions thereof) constitute a single connector. It appears from the present state of the art that such connectors may well be improved in respect to their electric contacting portions by which to achieve more efficient current transmission. Experience with connectors of said duplicate-form type indicates that they lack an effective electrical contacting means which functions independently of their mechanical connecting means.

Thus it is a purpose of this invention to produce a simple two-part duplicate-form quick-disconnect electrical fitting having joining or clasping portions which possess a dual-connecting function, the two primary features of which include a first means for producing a sustained spring-loaded pressure engagement to establish an effective electrical contact for transmitting current, together with a second means for making a mechanical connection for holding the two parts together against strain, and wherein the two means operate to supplement each other but function independently.

The foregoing combination of the two primary features affords a latitude in selecting manufacturing tolerance, especially so in respect to the first means controlling the degree of tension of the spring-loaded portion of the terminal which acts to make the electrical connection. In other words, the manufacturer may select and build into this new terminal a chosen degree of resilient spring-loaded tension which is best adapted to the particular use to be served by a manufactured lot of the connectors—having regard to size of the fitting and purposes served in the field—without altering the positiveness of its mechanical connecting means. It is found that this feature is important in respect to the duplicate-form type of terminals in general and increases the utility thereof.

Another purpose is to produce an electrical connector of the duplicate-form type (embodiment the foregoing features) having a camming-

2

resistance function which produces an audible "click" or pronounced "snap" as two of the terminals are manually engaged and disengaged, thereby indicating by sound, as well as by "feel" imparted to one's fingers, that the two parts are in finally connected position. This audible feature is important where wiring installations and connections to be made are not visible to a mechanic and he must sometimes "reach for" as well as "feel out" and "hear" the connection and disconnection being made.

A further purpose is to produce a duplicate-form two-part electrical connector, each terminal of which is so arranged in its structural contour that two thereof can be plugged together solely and only in correct relation to establish a connection. This provision makes the connector fool-proof and inhibits its use other than in accordance with the mode of operation as particularly featured in the next above paragraph. This purpose of the invention is carried out by a modified form of the invention.

THE DRAWINGS

25 The description herein and the accompanying drawings explain the principle of the invention, point out its main purposes, present it as preferred at this time, demonstrate its features in order to disclose the scope of the invention, thus suggesting further examples which may develop out of and occur to others from the teachings herein, and also aid in understanding the problems sought to be solved.

Sheet 1 of the drawings illustrates the structural form of a single terminal, two of which are required to make a complete electrical terminal clasp connector as shown on Sheet 2.

Fig. 1 shows a plan or face view, being the inside contact face of the terminal.

40 Fig. 2 shows an elevation of the outer end, that is, the wire-receiving sleeve-end of the terminal.

Fig. 3 shows a transverse section on the line 3—3, which may be viewed from Figs. 1 and 5, looking toward the inner end of the terminal.

45 Fig. 4 shows a transverse section on the line 4—4 looking toward the outer or wire-receiving sleeve-end of the terminal but omitting said sleeve-end for clarity.

50 It is observed that Figs. 3 and 4 are so placed on the drawing that the inside electrical contacting surface of the terminal in each view faces the other.

Fig. 5 shows a side elevation of the terminal; and Fig. 6 is a mid-longitudinal section thereof.

Fig. 7 illustrates a modified construction (a second form) of the twin terminal which is characterized by its non-symmetrical shape in respect to certain portions thereof. This feature serves positively to prevent two of the identical terminals from so much as preliminarily interengaging. It fulfills the last above mentioned purpose concerning the fool-proof characteristics of the terminal.

Sheet 2 of the drawings shows action-views illustrating in sequence the manual operations (say three) performed and the positions reached when manipulating two of the duplicate-form or twin terminals into assembled relation to make a complete electrical connector.

Fig. 8 shows a side elevation of the two terminals spaced apart in aligned position ready to be preliminarily engaged.

Fig. 9 also shows a side elevation, but the two terminals now are in actual preliminary engaged position, before displacing them longitudinally and relative to each other, and before snapping them into final clasp-connected relation. Thus, Fig. 9 shows the first position.

Fig. 10 is a side elevation showing that the two terminals have been displaced lengthwise on each other and brought to a position ready to be (but before being) snapped together in final connected relation. This is the second position.

The next three views show the third position of the two duplicate-form terminals in finally clasp-connected relation—by which is attained the dual connection heretofore emphasized, that is, a mechanical joinder and an electrical connection, each supplementing the function of the other but acting independently, as hereinafter more fully explained.

Fig. 11 shows a plan view of Fig. 10 but after the two terminals have been snapped together in final connected relation.

Fig. 12 is a fragmentary view of a mid-longitudinal section of the connector in final position, the same as in Fig. 11; and Fig. 13 is a transverse section on the line 13—13 of Figs. 11 and 12.

It is seen that the latter two views are drawn to a scale much larger than previous views. Such illustration is for the purpose of clarity of those structural portions which provide the previously mentioned camming-resistance function for imparting the "feel" and audible "snap" when connecting and disconnecting a pair of the terminals. Furthermore, the two enlarged views show the several sustained spring-loaded pressure engaging areas constituting the outside and inside contact surfaces of the two joined terminals.

The drawings illustrate the invention by showing what is known as a "splice" or a "line" connector, that is, one for joining two wire ends. However, it will be appreciated that the invention also is adapted to other types of connectors of the "lug" form, the "eyelet" type, etc., for panel, instrument, and machine-wiring installations where splicing as such is not required.

The single terminal illustrated (Sheet 1) as an example of the invention, and the pair thereof assembled to produce a complete connector (Sheet 2), is drawn from specimens produced and tested, the drawings being set out to approximate scale. Accordingly, the fitting may be reproduced in various sizes from the drawings, in view of which fact the dimension-form and proportions thereof need not be described in detail.

Structural form of single terminal on Sheet 1

Further reference now is made to the drawings for a more detailed description of the illustrated

example of the invention. One of the terminals is first described (Sheet 1) and thereafter the assembly of a pair of such terminals (Sheet 2) will be explained in connection with the new mode of operation and enhanced utility of the connector.

The electrical terminal includes a substantially straight bar in the form of a shank 2 with a wire-receiving sleeve 3 carried on its outer end. An electrical conductor or wire W is shown (Figs. 5 and 8) as being secured to the outer end (the sleeve 3) of the terminal in any known manner.

The method of providing a suitable form of wire-receiving means, in the form of a sleeve 3, on the outer end of the terminal shank 2 may be adopted from the Thomas, Jr., Patent 2,275,163 showing a known form of electrical connector manufactured and sold under the registered trade-mark "Sta-Kon" by the same assignee as herein. Reference also is made to this patent for an understanding of one satisfactory method of establishing a solderless connection between the wire W and the sleeve 3 on the outer end of the terminal 2. The connector herein is new in respect to its inner end portion, as will be seen from this description and its drawings or by actual use of the connector, as further explained in reference to its new principles and mode of operation.

The terminal shank 2 as a whole is made of nominally hard metallic bar stock which is tempered to resist any tendency to bend permanently out of shape when subjected to service and also to impart resiliency for obtaining a degree of flexure by which to tension its inner contacting end portion.

A pair of hook-like clasps, in the form of ears 4, is formed on opposite edges of the shank 2 inwardly of the wire-receiving sleeve 3. The portion of the terminal comprising its inner end is set at an angle and also deformed or convexed to produce a bowed resilient portion 5 which is curved away from the clasping ears 4 and away from the plane of the shank 2. In other words, the inner end 5 of the terminal is bowed away from the axis of the wire-receiving sleeve 3 and hence away from the longitudinal axis of the shank 2.

The bowed resilient portion 5 is provided with a pair of cut-outs forming a reduced neck 6 opposite each other on the two side edges of the shank adjacent the ears 4, said cut-outs and ears being disposed symmetrically in relation to the lengthwise axis of the shank 2. A flat imperforate contact head 7 also is formed at the inner or far end of the bowed portion 5. The contact head 7 has a transverse length slightly more than the width of the bowed shank portion 5 and thus provides a pair of abutment-latching shoulders 8 near the inner end of the terminal at its side edges.

Next, it is seen that a boss in the form of an oval rib 9 is raised on the inside surface of the bowed resilient portion 5 adjacent the clasping ears 4. In other words, the rib 9 is located in the reduced neck portion 6 formed between the two cut-out notches. Such rib has a length somewhat greater than its height above the surface of the bowed shank portion 5 and is disposed transversely of the longitudinal axis of the terminal as a whole. The transverse rib 9 is contoured or ovaled to form a camming surface.

As later seen, the rib 9 provides for the camming-resistance action heretofore emphasized in connection with the audible "click" produced by a pair of terminals 2 when they are placed together and "snapped" into final connected rela-

tion. This rib is formed on the inside contacting surface of the terminal (the surface facing the ear pair 4) by swaging the outside surface of the shank inward, thereby leaving on said outside surface a depression which is the counterpart of the oval rib raised on the inner surface of the shank, as in Figs. 3, 4 and 6.

The clasping or retaining ears 4 are formed up from the edges of the shank 2 a distance spaced somewhat greater than the thickness of the shank material and are rigid or stiff with the shank. In other words, the inside contact surface of the shank 2 and underneath contact surface of the rigid ears 4 face each other and are disposed in parallel planes which are spaced apart a distance greater than the thickness of the material of which the terminal is made. For example, said spacing may be about one and one-half (1½) times the thickness of the shank 2 for achieving good performance when connecting two of these terminals together.

Next, it is explained that the width of the cut-out neck 6 has its parallel edges spaced apart slightly less than the distance between the formed up ears 4. The cut-out neck 6 may have its parallel edges curved outward, as shown, to merge with the base of the ears 4 that is, to meet the side edges of the shank 2 at or near the inner ends of the ears. Note also that the inner corners of the ears 4 may be relieved or rounded off, as shown. Thus, the two ears 4 and the two cut-out notches 6 are of symmetrical form, as distinguished from the modified type of terminal shown in Fig. 7 and later described.

By reason of the foregoing structural features, it follows that a pair of these duplicate-form terminals 2 can be placed or clasped together by passing the cut-out neck 6 of each terminal into position between the ears 4 of the other. This is observed in Figs. 8 and 9 where two of the terminals are being initially placed, each within the other. It is observed that the inside contact surfaces of the two terminals are facing each other, while their outside contact surfaces are turned away from each other.

The characteristics of the bowed resilient end portion 5 of the terminal are best understood by examining Fig. 5. It is observed that a dot-and-dash reference line 10 coincides with and represents the plane of the inside contacting surface of the shank 2. Then let a second reference line 12, which coincides with the flat contact surface of the terminal head 7, represent the angular relation between the plane 10 of the inside surface of the shank 2 and the plane 12 of the contact surface 7. The vertex of the angle included by the two reference lines 10 and 12 is located at or proximate the inner end of the ear 4, but such location is by way of example and is not critical.

In the illustrated example of the invention, the included angle between the two above explained reference lines 10 and 12 may approximate two and one-half (2½°) degrees. This angular relation is not critical but is found to impart effective spring-loading tension and to result in good performance when joining two of these terminals to complete an electrical connection having the dual-function connection heretofore emphasized as a feature of the invention.

Next, the distance or depth of the outward curved or bowed resilient portion 5 is shown on the drawings as being deformed away from the plane 10 (Fig. 5) of the shank 2 a distance about equal, more or less, to the thickness of said

shank or even a little greater. This angular arrangement and the contour drop of the bowed end 5 provide effective operation when two of the twin terminals are manipulated into final clasp-connected relation. Such arrangement also affords flexure of the resilient bowed portion 5 as it compressively spring-loads with sustained tension in coacting with the inside contact surface of another terminal shank 2 and with the clasping-hook ears 4 of the latter when interlocked therewith.

The resiliently and angularly-disposed bowed portion 5 is adapted to spring or flex and compress (tends to flatten out) toward and on the plane 10 (Fig. 5) and hence against the inside contact surface of the shank 2 of another terminal—this by virtue of a compressing and energizing action applied to said bow 5 by said other terminal as next described. The flexing fulcrum of the inner bowed end 5 is proximate the vertex of the reference-plane lines 10 and 12 adjacent the inner ends of the rigid ears 4. It is seen that these ears hook inward toward each other over the inside surface of the shank 2 and are spaced apart a distance at least equal to or may be greater than the width of the symmetrical cut-out neck 6.

Operation and utility, Sheet 2

30 As stated before, Figs. 9, 10 and 11 demonstrate the three-step manipulating sequence when joining a pair of the duplicate-form double-contacting surface terminals heretofore described, and the other views supplement my explanation of the new function and operating principle.

40 A pair of the terminals 2 initially are placed with their inside contact surfaces facing each other but spaced apart and with the inner edges of the ears 4 of both terminals close to or abutting each other (Fig. 8). Thus their outside contact surfaces are turned away from each other. Thereupon, the pair of shanks 2 are brought together by relative perpendicular motion to pass the cut-out neck 6 of each terminal through the spaced ears 4 of said each terminal (Fig. 9). Now it is seen that the two ovoid transverse ribs 9 are spaced from each other, and that the two terminals are loosely and preliminarily placed one into the other—the first position (Fig. 9).

45 Thereupon and secondly, the two terminal shanks are given a "pull" along their lengthwise axes (moving away from each other) to separate their ears 4 and to bring together their ribs 9. This is accomplished by holding the outer end of each sleeve 3 in each hand. As the ears 4 freely move apart (from Fig. 9 to Fig. 10 position) without resistance, the two ribs 9 approach each other and finally come into abutting relation with the first "feel" of resistance to further separating motion. Thus the ear pair 4 on one terminal retreats from the ear pair on the other, while the two ribs 9 approach each other during the second manipulation—this being a characteristic which is new in structural form and operation for electrical connectors of the duplicate-form class.

50 It is now seen that each bowed resilient portion 5 slides under pressure into position under the respective clasping ears 4 and is tensioned by reason of the outside contact surface of each said bowed portion crowding under and partially flattening out (reducing its bow) against the in-

side contact surface of each of the two rigid ears on both terminals 2. The rigid ears 4 of both terminals cause the inner end portions 5 of said terminals to flex at the vertices of the contact planes 10 and 12 on said terminals, thus urging the two imperforate or solid contact heads 7 into coincidence with the planes 10 and hence the shanks 2—at the end of the second manipulation, as shown (Fig. 10).

Thirdly, the terminal pair 2 and 2 now is given an additional pull against the resilient camming-resistance offered between the two contiguous ribs 9. A definite pull overcomes the resilient resistance by causing the ovaled surfaces of the two initially-engaged ribs 9 to climb or cam over and past each other into final interengaged relation (Figs. 11 through 13). As the two ribs 9 undergo this camming action, and each reaches the opposite side of the other, they "click" down on said opposite sides (still engaging each other) with an audible "snap" due to the cumulative spring-loaded impact of each rib against the inside contact surface of the shank 2 of the other terminal.

According to the foregoing, the two terminals are now interlocked against disconnection except by a definite and intentional pushing force applied in a direction opposite to that described above and are secured against tendency to loosen due to vibration. Now it is seen that the two flat-plane contact heads 7 are pulled longitudinally and compressed laterally into tensioned engagement with the inside contact surfaces of both shanks 2, and that the outside contact surfaces of both bowed portions 5 are compressed and clasped with tensioned engagement within and by the inside contact surfaces of the retaining ears 4. This final clasp-connected position of the two ovaled ribs 9 is best seen in Fig. 12 (enlarged view) where the two ribs have cammed by and "snapped" over each other in final latched position.

A definitely audible "snap" results from the cumulative impact of both spring-loaded camming ribs 9—thus assuring the operator that he has established an effective connection, one which he "feels" as well as "hears," thereby rendering unnecessary an inspection of the fitting and its connected wiring W. Of importance are the relative positions of the pairs of "spaced ears 4" and the two "contiguous ribs 9" when in final-clasp connected position, comprising new features in this class of duplicate-form terminals for producing electrical connectors.

With the foregoing in mind, it will be observed that the inner angular and bowed resilient end 5 of each terminal shank 2 is tension energized due to the pressure applied by the rigidity of the engaging ears 4 of the other. Consequently, the contacting head 7 on each bowed portion becomes spring-loaded and, therefore, is maintained under sustained bearing pressure against the flat inside contact surface of the other terminal shank.

It is important to note that there are a number of contacting areas under sustained spring tension when the terminal pair 2 is in final clasp-connected relation and that all surfaces are "wiped" clean by the sliding pressure of each terminal against the other—thus scraping and "de-oxidizing" the contact surfaces. These are important functions which reduce to a minimum the resistance to current flow through the connector.

The several areas of electrical contact are

75 apparent. For example, the "two" contact heads 7 engage each shank, with "four" ears 4 also engaging each bowed portion, as well as the oval surface of the ribs 9 engaging each other under pressure to make "one" additional contact. Altogether, there are "seven" contacting areas under spring-loaded pressure which provides an unusually effective electrical connection for transmitting current without likelihood of the fitting becoming heated.

It is observed that the two latching shoulders 8, adjacent each contact head 7, thus four in all, come into abutting relation with the outer end edges of the ears 4 when the connector is in final latched position (Figs. 11 through 13). This feature provides for a positive and independent mechanical connection and insures against accidental disconnection.

Also, it is seen that the foregoing construction and mode of operation provides for spring-loaded undiminished pressure contact between the terminal pair to establish the electrical connection independently of the mechanical connection afforded by the shoulders 8 stopping against the outer ends of the ears 4.

The joined terminals are readily disconnected by reversing the above described manipulation, that is, by longitudinally sliding the two terminals on each other until the ears 4 come back into contiguous relation (Fig. 9) whereupon each terminal can be lifted out of the other (Fig. 8).

In engineering this connector for production, it will be appreciated that the included spring-loading or energizing angle between the reference lines 10 and 12 (Fig. 5) may be varied. Likewise, the depth or drop of the bowed resilient portion 5 may be varied in relation to the plane 10 of the inside contacting surface of the shank 2. These features enable the manufacturer to produce the connector within chosen tension limits—by which to achieve a maximum or medium or minimum spring-tension contact—without in any way affecting the positive and independent mechanical connection afforded by the shoulders 8 engaging the ears 4.

Finally, it is pointed out that experience had with this invention and successfully testing numerous exemplary forms thereof do not indicate that a wiring mechanic or even a novice is likely to place the two terminals in the wrong position when making an electrical connection. In other words, a pair of terminals 2 only register for proper "feel" and "snap" connection when their hook-like clasping ears 4 are placed toward each other, that is, with the inside contact surfaces facing each other (Fig. 8).

It is also obvious that if the outside surface of one terminal is initially placed toward the inside surface of the other that they do not establish a clasping hold on each other. Thus a person using the connector will immediately turn the two terminals face to face (Fig. 8). However, the scope of the invention—breadth of its novelty, utility and variety of industrial applications in simplifying wiring installations—begets numerous variants in structural form, all of which cannot be illustrated herein. It appears, however, that one modification (Fig. 7) may be preferred by some users due to its ultra fool-proof characteristics next described.

The alternate type of duplicate-form terminal shown in Fig. 7

In this second form of the terminal, two of which also are required to produce an electrical

connector, additional or new part numbers are employed on the drawing to indicate the features which distinguish it from the first form (Figs. 1 through 6).

Accordingly, the same general form of the previously described shank 2 is here seen (Fig. 7) to have the bowed resilient inner terminal end 5 with a contact head 7 of imperforate form and a camming rib 9. Such rib has a smooth half-round contour raised transversely on the inside contact surface of the terminal.

The duplicate-form terminal is here modified by a cut-out neck having one edge 14 curved outward to meet the inner end of an ear 15 at that side edge of the shank 2 where the ear is formed thereon. The rounding portion 14 on one side of the notched-out neck and the rounded inner corner of the ear 15 on the same side are, in effect, the same in contour as the ears 4 and neck 6 heretofore described.

The other side of the neck of this modified form of terminal (Fig. 7) is seen to have a straight cut-out notch 16 with square corners and also a square-cornered ear 17. In other words, the notched edge 16 and the ear 17 may conform in respect to their right-angular shapes shown—square corners for the notch 16 and for the ear 17. Thus it is seen that the opposite sides of the terminal are non-symmetrical, in that the opposite notches 14 and 16 do not match and the same is equally true of the two opposite ears 15 and 17. The shaped contours shown are by way of example and not critical as to the species of the invention herein shown.

With the foregoing in mind, it will be observed that a pair of terminals of the Fig. 7 type cannot be placed together in the wrong position. By this is meant that the non-symmetrical neck 14, 16 of one terminal will not pass through the spaced ears 15 and 17 of another identical terminal to thereby improperly engage. The two terminals, therefore, are required to be turned with their inside contacting surfaces toward each other (the same as in Fig. 8), in order to achieve even a preliminary engagement of the two terminals when clasping them together to make an electrical connector.

In other words, the modified form of terminal (Fig. 7) is fool-proof in that two of the terminals cannot be so much as initially placed together, even in loose relation, unless their inside contact surfaces are facing each other (Fig. 8). This is due to the fact that the opposite sides of the terminal are distinguished by their non-symmetrical form, and that the cut-out neck 14, 16 of one will only receive the clasping ears 15, 17 of the other when placed together in proper relation (Fig. 8).

The two examples of the construction shown amply serve to emphasize the production possibilities in adapting the invention to chosen forms, a number of which may be made in accordance with the principles of this invention without departing from the spirit thereof.

The new principle and operating characteristics of the inner bowed end 5 and its contact head 7 may be achieved by other simple and equivalent forms of construction susceptible to "compression" by the rigid ears 4 for the purpose of "spring-loading" each twin terminal with equal "tensioned energy." For it is by this feature that the twin terminals "clasp" each other under "sustained-pressure contact" for effective electrical-current transmission "independently" of the action of the latching shoulder means 8. Although the contact

head 7 is shown imperforate, such formation is by way of example. Accordingly, it will be appreciated that "compression" by the rigid ears 4 may be achieved in other forms of inner-end construction of the terminal.

The disclosure herein explains the principles of the invention and the best mode contemplated in applying such principles, so as to distinguish the invention from others; and there is particularly pointed out and distinctly claimed the part, improvement or combination, which constitutes the invention or discovery, as understood by a comparison thereof with the prior art.

This invention is presented to fill the need for a new and useful electrical terminal clasp connector. Since various modifications in construction, mode of operation, use and method, may and often do occur to others skilled in the art, after acquaintance with a particular invention, it is to be understood that this disclosure is exemplary of the principles and of equivalent constructions without being limited to the present showing of the invention.

What is claimed is:

- 25 1. An electrical terminal comprising a straight flat shank having side edges as well as an inside contact surface and an outside contact surface, with a wire-receiving means at its outer end, and including a resilient inner end portion which is disposed at an angle to the straight flat shank and which is adapted to flex toward the plane of said shank, a neck provided in the terminal, a pair of oppositely disposed ears formed on the side edges and spaced from the inside contact surface of the shank, the two ears being spaced apart a distance not less than the width of the neck, and the two ears also having inside contact surfaces parallel with and also spaced from the inside contact surface of the shank a distance greater than the thickness of said shank.
- 30 2. An electrical terminal according to claim 1, in which an ovaled rib is formed on the resilient inner end portion, said rib being raised on the inside contact surface of said resilient inner end portion, and disposed transversely of the longitudinal axis of the terminal.
- 35 3. An electrical terminal according to claim 1, in which the vertex of the angle, as made by the resilient inner end portion and the straight flat shank, is located proximate the inner end edges of the ears.
- 40 4. An electrical terminal according to claim 1, in which the resilient inner end portion, as formed at an angle to the straight flat shank, is bowed away from the plane of the inside contact surface of the shank a distance greater than the spacing of the ears from said shank.
- 45 5. An electrical terminal according to claim 1, in which the resilient inner end portion, as formed at an angle to the straight flat shank, is bowed away from the plane of the inside contact surface of the shank a distance greater than the spacing of the ears from said shank.
- 50 6. An electrical terminal according to claim 1, in which the resilient inner end portion, as formed at an angle to the straight flat shank, is bowed away from the plane of the inside contact surface of the shank a distance greater than the spacing of the ears from said shank, and a contact head with a flat surface formed on the inner end of the bowed portion, the contact head being spaced from the plane of the shank a distance less than the spacing between the bowed portion and said shank, and the contact head being adapted to flex toward the plane of the shank.
- 55 7. An electrical terminal according to claim 1, in which the resilient inner end portion is bowed away from the plane of the inside contact surface of the shank, and a contact head formed at the inner extremity of the bowed resilient portion, the contact head having a flat surface which

11

is spaced from and at an angle to the plane of the inside contact surface of the shank.

7. The electrical terminal described in claim 6, in which the angle of the flat surface of the contact head is approximately two and one-half (2½°) degrees.

8. An electrical terminal according to claim 1, in which the neck is formed within the resilient inner end portion, and which neck is thus disposed at an angle to the plane of the straight flat shank.

9. An electrical terminal according to claim 1, in which the ears are rigidly formed, and a portion of the resilient inner end angular portion is bowed away from the plane of the straight flat shank, and is adapted to be compressed and the curvature of said bow reduced toward said plane.

10. An electrical terminal according to claim 1, in which the ears not only are rigid in themselves, but said ears also impart stiffness to the straight flat shank at the vertex of the angle, as made by the shank where it meets the resilient inner end portion, thereby providing for flexure of said resilient inner end portion proximate the ears, while the shank holds its straight flat form from the ears outward to the wire-receiving means.

11. An electrical connector comprising, in combination, a pair of duplicate-form terminals, each of which has a straight flat shank with a wire-receiving means on its outer end, and including a resilient inner end portion disposed at an angle on each straight flat shank, a neck formed in each terminal adapting the connector to be disengagably connected, ears spaced from the inside surface of the shank a distance not less than the thickness of said shank, said ears being rigid and receiving the neck of the other terminal and flexing each resilient inner angular-end portion into compressed spring-loaded pressure-sustained engagement with both shanks thus establishing an electrical connection, and shoulders formed on the inner extremity of each resilient inner angular-end portion and engaging the outer ends of the ears thus establishing a mechanical connection independently of the electrical connection.

12. An electrical connector according to claim 11, in which each resilient inner angular-end portion has a bowed formation curved away from the shank of the other terminal, and also in which the rigid ears clasp each bowed formation and compress same against the shanks.

12

13. An electrical connector according to claim 11, in which a camming rib is formed crosswise on each resilient inner angular-end portion, and in spring-loaded engagement with each other, as well as in spring-loaded engagement with each straight flat shank, and said camming ribs being adapted to climb over each other while spring-loaded and to produce an audible "snap" when connecting and disconnecting the terminals.

14. An electrical connector according to claim 11, in which each resilient inner angular-end portion has a bowed formation curved away from the shank of the other terminal, and also in which the rigid ears clasp each bowed formation and compress same against the shanks, a camming rib formed crosswise on each resilient inner angular-end portion, and in spring-loaded engagement with each other, as well as in spring-loaded engagement with each straight flat shank, and said camming ribs being adapted to climb over each other while spring-loaded and to produce an audible "snap" when connecting and disconnecting the terminals.

15. An electrical connector comprising, in combination, a pair of duplicate-form terminals, each of which has a shank with wire-receiving means, and including a resilient-contact portion capable of being compressed to energize said portion with spring tension, a neck formed on each terminal adapting the terminals to be disengagably connected, and hook-like ears disposed opposite each other and with a space left between them on each terminal for receiving the neck of the other terminal, the ears spaced from the inside surface of the shank a distance not less than the thickness of said shank, said ears being rigid and applying compression to the resilient-contact portion of said each terminal to spring-load both thereof into sustained-pressure contact with each other.
